UNITED STATES PATENT OFFICE.

JAMES R. LATHAM, OF NEW YORK, N. Y., AND FRANK E. WILLIAMS, OF ALHAMBRA, CALIFORNIA.

FASTENING.

SPECIFICATION forming part of Letters Patent No. 508,027, dated November 7, 1893.

Application filed February 18, 1893. Serial No. 462,936. (No model.)

To all whom it may concern:

Be it known that we, JAMES R. LATHAM, residing in the city, county, and State of New York, and FRANK E. WILLIAMS, residing at 5 Alhambra, in the county of Los Angeles and State of California, citizens of the United States, have invented a new and useful Fastening, of which the following is a specification.

This invention relates to fastenings designed to be applied to boots or shoes, gloves, corsets, or other articles to which it may be adapted, that are arranged to be engaged and operated by a device for connecting the male and female members of the same.

15 The object of the invention is to dispense with the use of ordinary button-holes and buttons, to obviate tearing away of the several supports of fastenings, and also the insertion of a buttoning device through an opening.

20 The invention consists of the construction, arrangement, and combination of the parts in relative detail and as a whole, as will be more fully hereinafter described and claimed, together with all equivalents or analogous 25 structures that may hereinafter appear.

In the drawings: Figure 1 is a perspective view of a shoe, showing a fastening applied thereto contemplating the invention and broken away to illustrate the position and operation of a buttoning device in connection therewith. Fig. 2 is a detail perspective view of the parts of the fastening detached and shown on a larger scale. Fig. 3 is a transverse central section of the two members of the fastening shown in engagement with each other. Fig. 4 is a detail perspective view of the male member of the fastening embodying the invention and shown formed with a spring action. Fig. 5 is a detail perspective view of 30 the male member of the fastening shown of solid form and embodying the invention. Fig. 6 is a detail perspective view of the male member of the fastening, showing the same arranged to be sewed or secured by stitches 45 to its support.

Similar numerals of reference indicate corresponding parts in the several figures of the drawings.

Referring to the drawings, the numeral 1 50 designates the female member of the fasten-

ing, which is shown by Fig. 3 in one form, and consists of a tubular core 2, with a flanged head 3, and a lower inwardly-bent circumferential shoulder 4, interiorly arranged. The lower end of the core 2 projects below the 55 said shoulder and is arranged to be turned up against a washer or plate 5 and fit in a slight indentation 6 to shield the end of the same. The upper part of the core 2 is surrounded by a covering of vulcanized rubber, 60 paper-pulp, papier maché, or other composition of matter, as at 7, to form a head and a lower bearing flange that rests upon the outer surface of the material to which said female member is applied. This is one form of the 65 female member, but it will be understood that other forms may be equally well used and the invention is not in the least limited by the foregoing description.

As shown clearly in Figs. 2 and 3, a male 70 member 8 is shown that consists of a base or floor plate 9, having securing prongs or legs 10, that are passed through the material of the article on which the fastening is employed, and the rearmost side of the said base or floor 75 plate is formed with an entrant curved recess 11, having the inner wall, at the center, deflected downwardly, as at 12, to form a concave guide. The said base or floor plate is also formed with a series of slots or openings 80 13, that extend therethrough and through which are passed the prongs or legs 14 of a flange 15, of a stud or post 16, forming the male member of the fastening. The said prongs or legs of the flange are bent under 85 the base or floor plate to thereby firmly secure the two parts together, and the stud or post 16, at the rear thereof and over the guide formed by the deflection 12 of the base or floor plate, is provided with an opening 17, 90 that extends inwardly thereinto from one side thereof, as shown, by removing a part of the flange 15 at said point. It will be seen that the deflection 12, together with the opening 17, forms a socket in the male member for a 95 purpose that will be fully hereinafter set forth. In Fig. 4 the said male member of the fastening is shown provided with a spring-head 18, and the socket is located in the base-flange of the same and at the rear in a man- 100

ner similar to the form heretofore set forth. In Fig. 5 the male member of the fastening is shown of solid form, and the socket is located therein slightly above the base of the same, thereby illustrating that if desired, the said socket may be positioned at any point so long as a convenient engagement thereof may be obtained.

As shown in Fig. 1, the fastening herein set forth in its various forms is arranged for use in connection with a buttoner that will now be set forth for the purpose, solely, of describing the function of the socket in the male member of the fastener. The said buttoner comprises a shank 19, having a suitable handle at the upper end of the same, and a lower heel 20, and an engaging toe or finger 21, and an arch 22, intermediate of said heel and toe or finger. Above the said lower engaging end of the buttoner is pivoted the inner end of an arm 23, having an outer engaging end 24. In operation, the toe or finger is slipped into the socket, and being guided thereinto by the deflection 12, while the arch 22 stands above the material of the shoe or other device to which the fastening is applied, and the heel bears on the said shoe or other device in rear and away from the point of application of the said male member of the fastening. At the same time that the toe or finger is inserted into the socket, the engaging end 24 of the arm 23 is caused to take over the exteriorly-projecting head or enlargement of the female member that is carried by the flap or fly of the shoe or other adjacent part to be secured, and by moving the shank of the buttoner backwardly the fly or flap is drawn over simultaneously with a similar movement of the female member of the fastening to cause the two parts of the fastening to be detachably connected. The manner of construction and engagement of the lower end of the shank of the buttoner prevents loosening or twisting of the male member of the fastening and causes the same to be raised upward into and connected to the female member of the fastening without any inconvenience to the op-

erator or injuring the article to which the fastening may be applied.

The exterior head or enlargement of the female member of the fastening that is acted upon by the engaging end of the arm 23 is formed with a slight rim or under depression in order to facilitate the proper operation of the arm 23 therewith, and it will be understood that the said head or enlargement may be shaped, ornamented, or colored in any desirable and necessary manner; and while specific forms of fastenings have been described, it will be understood that the form of the fastening will not in the least alter the gist of the invention, so long as the socket is employed in connection with the male member; and it will therefore be obviously apparent that changes in the form, proportion, and the minor details of construction may be resorted to without departing from the principle or sacrificing any of the advantages of this invention.

In Fig. 6 the flange or lower securing plate is shown, formed with a series of openings whereby the male member of the fastening may be attached to its support by stitches or sewing the same in any preferred manner.

Having described the invention, what is claimed as new is—

1. A fastening composed of a female member provided with a socket, and a male member, the latter having an opening in the side thereof, said opening being arranged for removable engagement or insertion of the end of a buttoner, substantially as described.
2. A fastening composed of two members, one of which is flanged and having a depression in the said flange and above which an opening is formed.

In testimony that we claim the foregoing as our own we have hereto affixed our signatures in the presence of two witnesses.

JAMES R. LATHAM.
FRANK E. WILLIAMS.
